PROCESS OF AND APPARATUS FOR THE PRODUCTION OF VISCOSE SOLUTIONS

Gustav A. M. Heim, Velp, Netherlands, assignor to American Enka Corporation, Enka, N. C., a corporation of Delaware

Application October 12, 1938, Serial No. 234,668
In Germany October 30, 1937

5 Claims. (Cl. 18—8)

This invention relates to the manufacture of artificial products from solutions, which are characterized by the fact that the degree of aging or ripening to which they are subjected prior to the formation of the products therefrom, materially alter the properties of the products. More particularly, the invention is directed to a process of and an apparatus for the production of rayon and other fibers from a plurality of batches of spinning solutions, the spinning of which is controlled in accordance with the degree of ripeness thereof in such manner that the solution actually being spun is maintained at a substantially constant degree of ripeness even throughout long spinning periods. While the invention will be described in its application to the manufacture of rayon threads from viscose, the invention is equally applicable to the manufacture of artificial products from other types of spinning solutions, and indeed, the benefits thereof may be had in the manufacture of any chemical compounds to the extent to which similar problems are encountered.

In the manufacture of rayon according to the viscose process, cellulose sheets are first soaked in a solution of sodium hydroxide to form alkali cellulose, and the excess lye is removed therefrom by pressure. Thereupon the alkali cellulose sheets are subjected to a shredding operation to reduce them to crumbs, and after a short aging period the crumbs of alkali cellulose are treated in a sulfiding churn with carbon bisulfide. The product of this reaction of the alkali cellulose with carbon bisulfide is cellulose xanthate, which upon being dissolved in a weak caustic soda solution forms viscose. Rayon filaments are spun from the viscose solution as thus formed by extruding the viscose through the minute orifices of a spinneret into a coagulating bath.

Viscose is not ordinarily used in its green or unripened state for spinning purposes, inasmuch as it has been found that, if the solution is allowed to age somewhat before spinning, the quality and uniformity of the spun product will be greatly improved. It has also been found that the spinning of viscose solutions of different ages results in the production of yarns having different physical properties, and the particular age at which viscose will produce a yarn having the desired properties has been a matter of concern and has involved much experimentation. It is generally conceded that viscose should be allowed to ripen up to a certain point or degree before it is passed on to the spinning machine, and that this degree of ripeness of the solution should

be maintained substantially constant as the spinning operation progresses. Furthermore, green viscose normally contains impurities which tend to clog the minute orifices in the spinnerets through which the viscose is extruded. It is customary to remove these impurities by repeated filtration of the viscose solution, and this is done as a part of the aging process, the solution being pumped through a series of aging tanks and filtered between each tank.

As stated above, viscose of different degrees of ripeness, when spun, will produce threads having different physical properties, and up until the present time slight variations of this nature in rayon spun from one and the same batch of viscose have been regarded as an unavoidable objection incident to the manufacture of rayon. The ripening of viscose progresses rapidly from the time it is formed until it passes through the coagulating bath of the spinning machine, and is customarily stored in so-called spinning or feed tanks from which is drawn the supply of viscose required by the spinning machines. These feed tanks are of such a size that several hours are required for the spinning room to use the entire contents of a single tank. The result is that a batch of viscose in a feed tank, which at the time it is placed therein is at the proper degree of ripeness for spinning, undergoes additional ripening before it is all utilized by the spinning machines, whereby variations in uniformity occur in yarn spun from a single batch of viscose. This is one of the serious obstacles that the rayon industry has encountered and for which up until the present time it has devised no satisfactory solution.

The present invention provides a process of and an apparatus for simply and effectively overcoming the difficulties referred to above and it contemplates generally the provision of a process and means for mixing with a constantly decreasing supply of aging overripe viscose, a constantly increasing supply of unripe viscose in such manner that the viscose mixture as it continues to flow to the spinning machine is of a predetermined and uniform degree of ripeness with the result that the product spun therefrom is uniform in physical characteristics.

It is an object of this invention to provide a process of and apparatus for continuously supplying a uniform spinning solution to meet the requirements of a spinning machine over prolonged periods of operation.

Another object of the invention is the provision of a process and means for delivering to a

spinning machine a continuous supply of a spinning solution having a uniform degree of ripeness from a plurality of sources while the solutions at the respective sources progress from 5 a state of unripeness to a state of overripeness during the spinning thereof.

A further object of the invention is the production of a spinning solution formed of unripe and overripe viscose solutions which, upon delivery to the spinning machines, will yield a product having uniform physical characteristics.

Other objects and advantages of this invention will be apparent from a study of the following detailed description, when considered in connection with the accompanying drawing, wherein:

Figure 1 is a diagrammatic representation of a spinning tank system formed in accordance with this invention, and

Figure 2 is a diagrammatic representation of a 20 system of spinning tanks formed in accordance with a modification of this invention by means of which results may be had comparable to those obtained by the use of the system of Figure 1.

In referring specifically to Figure 1, which illustrates the preferred embodiment of the apparatus of this invention, similar spinning tanks designated as 10, 11, 12, 13, 14, 15, 16 and 17 are connected by means of pipes 18, 19, 20, 21, 22, 23, 24 and 25 to a ring main 26. Connecting pipes 18, 30 19, 20, 21, 22, 23, 24 and 25 are each provided with respective stop valves 27, 28, 29, 30, 31, 32, 33 and 34.

Ring main 26 between the points of connection of adjacent pipes 18, 19, 20, 21, 22, 23, 24 and 25 35 is provided with respective stop valves 35, 36, 37, 38, 39, 40 and 41, and similar valves 42 and 43 are provided in the lower run of the ring main in opposite sides of a discharge pipe 44 which is connected into the main pipe.

40 A branch pipe 45 provided with a valve 46 is connected into the ring pipe 26 at a point which is adjacent the end of the lower run and remote from the section of the ring pipe which is under the control of valves 42 and 43. This branch pipe 45 is connected to pipe 44 at a point 47 spaced from the ring main. A similar branch pipe 48 containing a stop valve 49 is connected to the main 26 at a point on the lower run which is at the opposite side of the portion of the run controlled by valves 42 and 43. Branch pipe 48 is connected to discharge pipe 44 substantially at the same point at which branch pipe 45 is connected thereto. Discharge pipe 44, between ring pipe 26 and the point of connection of the branch 55 pipes 45 and 48, has a pump 50 arranged therein. Pump 50 is adapted to be driven at a varying speed by means of a conoid drive 51 which includes a driven shaft 52, a cone pulley 53, a belt 54, a longitudinally reversed cone pulley 55 and 60 a driving shaft 56. Beyond the point of connection 47 discharge pipe 44 is provided with a homogenizer or mixing device 57. Discharge pipe 44 beyond the homogenizer is connected to the spinning machine, or machines (not shown).

65 In the operation of the system illustrated in Figure 1, the spinning tanks 10, 11, 12, 13, 14, 15, 16, and 17 have viscose supplied thereto from a series of aging tanks (not shown). The supply of viscose to spinning tank 10 is received from 70 the oldest batch of viscose in the last aging tank and spinning tank 11 receives its supply of viscose from the next succeeding aging tank. The viscose solution supplied to spinning tank 10 has been ripened to the proper degree for spinning 75 whereas the viscose solution supplied to spinning

tank 11 is younger or unripened. Thus the viscose in tank 10 while being at the correct degree of ripeness will constantly age while the viscose in tank 11 which is not sufficiently ripened for direct spinning will constantly age and thereby approach and subsequently exceed the correct degree of ripeness.

At the beginning of a spinning period, which for example, may consume a weak, tank 10 for the reasons to be hereinafter discussed has only 10 half as much viscose delivered thereto as does tank 11 and therefore in practice tank 10 is half filled while tank 11 is completely filled. When utilizing all of the tanks 10, 11, 12, 13, 14, 15, 16 and 17, valves 27 and 28 are maintained open while valves 29, 30, 31, 32, 33 and 34 are closed. Valves 35, 43 and 49 are closed and valves 36, 37, 38, 39, 40, 41, 42 and 46 are open. The quantity of viscose to be withdrawn for utilization in the spinning machine is ordinarily controlled by two 20 factors. First, air pressure is exerted upon the viscose in the respective spinning tanks to force the solutions therefrom and, second, the quantity of viscose required by the spinning machines is controlled by pumps (not shown), which are placed at each individual spinning point, these two forces acting upon each other to maintain a state of equilibrium. More specifically, when operations are stopped on one or more spinning machines the viscose requirement decreases and the air pressure on the viscose tank is automatically reduced accordingly, and conversely when a spinning machine is again placed in operation the air pressure on the tank is increased to meet the added requirement of the spinning pumps. 35 Therefore, at the beginning of an operation the entire supply of viscose used by the spinning machines will be drawn from the tank 10 through a portion of ring main 26 and open valve 42, through pipe 44, pump 50 and mixing apparatus 51 directly to the spinning room. Pump 50 is operated by the conoid drive 51 in a manner to constantly decrease the quantity of viscose being withdrawn from tank 10. As the quantity of viscose supplied by tank 10 is decreased, the spinning machine pumps will withdraw from tank 11, which is under air pressure, a constantly increasing quantity of viscose. The viscose withdrawn from tank 11 passes through another portion of ring main 26 comprising open valves 36, 37, 38, 39, 40 and 41, and through branch pipe 45 and its valve 46, respectively, through the point of connection 47 beyond pump 50 thereby to balance the diminishing supply of viscose from the pump. The two viscose solutions being delivered from tanks 10 and 11 are as aforesaid of different degrees of maturity but they are passed through mixing apparatus 57 together where they are completely homogenized into a viscose solution of uniform ripeness before it is conducted 60 to the spinning machines.

The speed of the pump 50 is so regulated that after the lapse of about one-half the time during which the spinning room utilizes the contents of an entire spinning tank the pump supplies only 65 about one-half of the viscose solution required by the spinning machines. Therefore, when this point in the operation is reached, tanks 10 and 11 are each utilized to supply one-half of the quantity of the viscose solution required. At this stage of the operation conoid drive 51 is shifted so that pump 50 which has been operated at a constantly diminishing speed is then operated at a constantly increasing speed. At this same time valve 42 and 46 are closed and valves 70 75

43 and 49 are opened. Pump 50 immediately begins to draw viscose from tank 11 at a constantly increasing rate. The passage of the viscose from tank 11 is no longer directed through branch pipe 45 but instead it passes through valve 43 and into pipe 44, through the pump 50, and the mixing apparatus 57 while the residual viscose requirements are then drawn by the pumps of the spinning machines directly from tank 10 5 at a decreasing rate. The viscose from tank 10 is drawn through branch pipe 48 and valve 49 and is admitted to pipe 44 at point 47 whereupon it passes with the viscose from tank 11 into and through the mixing device for the purposes here- 10 tofore discussed. The decrease in the rate of feed of the viscose solution from tank 10 is in direct ratio to the speed at which the viscose is pumped from tank 11.

The constantly increasing supply of viscose 20 drawn by pump 50 from tank 11 reaches its maximum when the content of tank 11 is reduced by one-half and tank 10 has become empty. At this stage of the operation the entire spinning room requirements are supplied by tank 11 25 through the medium of pump 50. Valve 27 of tank 10 is now closed and the valve 29 of tank 12 is opened. Tank 12 has been filled with a viscose solution of a lesser degree of maturity 30 than that contained in tank 11 and the air pressure is placed upon the solution in the tank. As the operation continues valves 35, 42 and 46 are opened and valves 36, 43 and 49 are closed. The concid drive is now shifted over and the pump 50 begins to draw the viscose solution from tank 35 11 at a constantly decreasing rate through the ring main and valves 35 and 42 and pipe 44 while the additional viscose requirements are drawn from tank 12 as a result of valves 31, 38, 39, 40, 41 and 46 being open. The solution from tank 40 12 is mixed with the solution from tank 11 which is being drawn by pump 50 and the solutions are homogenized in the mixer 57 in the manner previously referred to.

When the contents of tanks 11 and 12 have 45 reached the stages of the contents of tanks 10 and 11 at the time that tank 12 was brought into the operation, valve 28 of tank 11 is closed and valve 38 of tank 13 is opened as well as valve 36 in the ring pipe 26, valve 37 is closed and the 50 series of valves are set as at the beginning of the operation. The withdrawal of the solutions from tanks 12 and 13 is then carried on in the manner previously described with respect to the now empty tanks 10 and 11 and as tank 12 becomes 55 empty the remainder of the tanks are brought successively into operation in the manner described in the operation of the other tanks. It will be clear from the above that the operation may be continued by the refilling of the empty tanks and the utilization thereof after the contents of each tank in the system has been utilized. However, the last tank to be utilized in a 60 complete spinning operation is supplied with viscose only to one-half of its capacity.

In the operation of the system here described, 65 it will be seen that the portion of viscose solution supplied by means of pump 50 is of a pre-determined amount at any stage of the operation. However, as noted above, the demand by the 70 spinning machine may vary somewhat from time to time. Under normal conditions of operation, wherein a large number of spinning machines are employed, the supply of viscose solution from the tank under air pressure will vary to compensate 75 for any irregularities in the demand. However,

care should be exercised to avoid substantial unbalance of the process if a relatively large proportion of the spinning machines are stopped during the spinning operation. In such case, the system is preferably readjusted to the new conditions by modification of the speed range within which the pump 50 operates.

The modified system illustrated in Figure 2 is provided with spinning tanks 58, 59, 60, 61, 62, 63, 64 and 65 and these tanks through the medium of pipes 66, 67, 68, 69, 70, 71, 72 and 73 which are provided respectively with valves 74, 75, 76, 77, 78, 79, 80 and 81 are connected to ring main 82. Arranged in the ring main between adjacent connecting pipes are valves 83, 84, 85, 15 86, 87, 88 and 89. The upper run of ring main 82 is provided at its end with parallel branches 90, 91 and 92 and the lower run of the main ring is provided with a similar series of branches 93, 94 and 95. The branches 90, 91, 92, 93, 94 and 95 20 have arranged therein valves 96, 97, 98, 99, 100 and 101 respectively. Discharge pipe 102 is connected into the ring main 82 at a point intermediate the two series of branches and a mixing apparatus or homogenizer 103 is provided in discharge pipe 102. Pipe 102 like pipe 44 of the system illustrated in Figure 1 is connected to the spinning machines (not shown).

In discussing the specific operation of the system illustrated in Figure 2 reference will be had 30 to a typical example. Tank 58 is first half filled with properly ripened viscose which is sufficient to last for a period of approximately 6 hours and tank 59 is completely filled with a younger or unripened viscose. Tanks 58 and 59 are both 35 placed under air pressure and valves 96, 97 and 98 are opened together with valve 74. The remainder of the valves are maintained closed and therefore the properly ripened viscose from spinning tank 58 at the beginning of the operation 40 supplies the full requirements of the spinning machines, the viscose passing from tank 58 through pipe 66 and valve 74 and then through branch pipes 90, 91 and 92, to and through discharge pipe 102 and homogenizer 103 to the spinning machines. After the system has been in operation for approximately 45 minutes, valve 75 45 is opened and valves 84, 85, 86, 87, 88, 89 and 99 are opened so that a small quantity of the unripened viscose from tank 59 will be supplied to 50 the mixing apparatus wherein it is homogenized with a correspondingly reduced proportion of viscose which is being drawn from tank 58.

After the system has been in operation for approximately another 60 minutes, valve 96 is closed 55 so that the flow of viscose from tank 59 will be increased as the flow of viscose from tank 58 is diminished. At the end of an additional 27 minutes, valve 100 is opened and valve 96 is reopened. At this stage of the operation valves 96, 97, 98, 60 99 and 100 are open and the flow of viscose from tank 58 is only slightly greater than the flow of the unripened viscose from tank 59. Upon the expiration of an additional 30 minutes, valve 96 65 is closed whereby the operation proceeds with two valves open in each of the series of branch pipes and therefore one-half of the spinning room requirements are supplied at this time from each of the tanks 58 and 59. As the operation is continued and after the expiration of an additional 70 36 minutes, valve 101 is opened and this will cause a slightly increased amount of viscose to flow from tank 59 as compared to that which is flowing from tank 58. Subsequently upon the lapse of 30 additional minutes, valves 97 and 101 75

- are closed. This causes the flow of viscose from tank 58 to pass through but one branch pipe, whereas the viscose flowing from tank 59 is being delivered through two branch pipes. There-
 5 after upon the expiration of an additional 27 minute period, valve 101 is again opened where-
 upon at the expiration of 60 minutes, tank 58 will have become empty and all of the valves of branches 93, 94 and 95 being open, the full re-
 10 quirements of the spinning room will then be drawn from tank 59. Tank 58 is now removed from the operation by the closing of valve 74 and tank 60 is brought into operation by placing the same under air pressure and opening valve 76.
 15 Valve 83 is now opened and valve 84 is closed as well as valves 99, 100, and 101. Valves 96, 97 and 98 are opened and the operation of the system is repeated in connection with the supply of viscose from tanks 59 and 60, the same as has been de-
 20 scribed in connection with the supply of viscose from tanks 58 and 59. When the supply of viscose in tank 59 has been exhausted, valve 75 is closed and tank 61 is brought into the operation by the closing and opening of appropriate valves
 25 and the system is continued to be operated as aforesaid. The system is continued to be operated by the utilization of the supply from each of the tanks and the tanks may be refilled as desired. It is desirable at the end of a complete spinning operation to fill the last tank only to one-half of its capacity.

With respect to the operation of the system of Figure 2 with reference to the withdrawal of viscose from tanks 58 and 59 as specifically set forth, the following table provides a summary thereof in tabular form:

TABLE

Change in status of proportioning valves 96, 97, 98, 99, 100, 101 after lapse of time periods indicated during withdrawal of viscose from tanks 58 and 59

	Time in minutes	Tank 58	Tank 59
45	0	96, 97, 98 open	99, 100, 101 shut
	45	96 closed	99 opened
	60	96 opened	100 opened
	27	96 closed	
	30		101 opened
	36		101 closed
50	30	97 closed	101 opened
	27		
	60	98 closed	101 opened

While the foregoing description sets forth my invention in its preferred embodiment with modification thereof, numerous changes may be made in the construction and operation thereof without departing from the spirit of the invention. Therefore, it is desired that the present embodiment be considered in all respects as illustrative and not restrictive, reference being had to the appended claims rather than to the foregoing description to indicate the scope of the invention.

What I claim is:

- 65 1. An apparatus for continuously effecting the formation of a spinning solution of predetermined maturity for use in a prolonged spinning operation in the manufacture of artificial products, comprising a plurality of supply tanks, means for

withdrawing from one of said tanks a decreasing quantity of spinning solution and for withdrawing from another of said tanks a correspondingly increasing quantity of spinning solution, said means including a changeable speed power driven 5 pump, and a homogenizer for mixing the spinning solution so withdrawn.

2. An apparatus for continuously effecting the formation of a spinning solution of predetermined maturity for use in a prolonged spinning operation in the manufacture of artificial products, comprising a plurality of feed tanks, a product-forming device, a pipe-line connecting said feed tanks and said product-forming device, means for withdrawing from one of said tanks a constantly 10 decreasing quantity of spinning solution and for withdrawing from another of said tanks a correspondingly increasing quantity of spinning solution, said means including a changeable speed power driven pump, and means for uniting said 20 solutions prior to delivery to said product-forming device.

3. In a process of forming synthetic products from a cellulose xanthate solution, the steps of regulating the quality of said products by employing a solution of a predetermined degree of maturity which comprise constantly withdrawing solution from a source of supply of under mature solution, constantly withdrawing solution from a source of supply of over mature solution, homogeneously mixing the said solutions as a continuing operation, changing the amounts of said solutions so mixed as the said solutions become more aged to constantly increase the proportion of the said under mature solution so mixed, conducting 30 said mixed solution to a product-forming device as it is formed and forming products from said mixed solution.

4. A process of maintaining constant the degree of maturity of a spinning solution for artificial products at the time of its extrusion from a product-forming device, comprising the steps of uniting as a continuing operation increasing proportions of a flowing premature spinning solution with correspondingly decreasing proportions of a flowing post-mature spinning solution in the path of flow of said solutions from sources of supply to said product-forming device, continuously conducting the united solution as it is formed to said product-forming device and continuously forming 50 products therefrom.

5. A process of effecting the formation of a spinning solution of predetermined maturity for use in a prolonged spinning operation in the manufacture of artificial products, comprising the steps of uniting as a continuous operation, predetermined proportions of a premature spinning solution with predetermined proportions of a post-mature spinning solution in the path of flow of said solutions from sources of supply to a product-forming device, forming products from the united solution and during the product-forming operation continuing the uniting of the solutions while decreasing the proportions of the post-mature spinning solutions and correspondingly increasing the proportions of the premature spinning solutions.

GUSTAV A. M. HEIM.
